UNITED STATES PATENT OFFICE

ROBERT MALCOM, OF CHICAGO, ILLINOIS

GOOGLE HEADBAND FASTENING MEANS

Application filed October 17, 1930. Serial No. 489,275.

My invention relates to means for securing the head bands to the eye-cups of a goggle; the object of the invention being to provide inexpensive means which enables the ends of the head-band, whether of elastic or non-elastic material, to be readily attached to the attaching members of the goggle without possibility of accidental dissociation of the parts; and at the same time to provide means whereby the free ends of the head-bands or straps will be adjustably and at the same time firmly secured together.

The objects and advantages of my invention will be more readily comprehended from the detailed description of the accompanying drawings, wherein—

Figure 1 is a perspective view of a goggle provided with my improved attaching means; merely the ends of the head-bands being shown.

Figure 2 is a cross sectional view of one of the eye-cups illustrating my improved attaching means with a portion of one end of the head-band and a portion of nose bridging means being shown.

Figure 3 is a perspective view of one end of a head-band or strap with my improved attaching member or clip.

Figure 4 is a sectional view taken substantially on the line 4—4 of Figure 3.

Figure 5 is a plan view of the blank, cut and scored for forming the clip.

Figure 6 is a perspective view of the clip partially bent ready to receive the end of the head-band therebetween.

Figure 7 is a detail sectional view taken substantially on the line 7—7 of Figure 1 and showing in dotted lines the manner of inserting the clip in place.

As the eye-cups or goggle proper, aside from the band attaching lug or ear, form no part of my present invention, a detailed description thereof need not be entered into.

In the specific exemplification of the invention, the outer side wall of each eye-cup 10 is provided with a cut-out portion or ventilating opening as at 11. This opening, in order to prevent the entrance of foreign matter, is provided with a suitable mesh screen, as at 12, held by a suitable metallic rim or

frame 13 which latter is provided with an integral ear 14 disposed laterally through the opening 11 in the wall of the eye-cup.

The ear 14, at its outer end, is preferably enlarged and provided with a transverse slot 15 adapted to receive the holding clip 16 secured to the end of each head-band or strap 17.

The head-band, which is preferably of more or less width, may either be composed of elastic material or non-elastic material and consists of two straps each having an end secured to one of the eye-pieces or cups 10 of the goggle.

My improved attaching means, as disclosed in the drawings, consists of the clip 16 composed of sheet metal originally cut to the shape disclosed in Figure 5 consisting of a flat blank, with the two opposite longitudinal sides provided with ears or lugs 18, 18 disposed at the vertical longitudinal center of the blank, while the other longitudinal opposite sides are preferably provided with the prong portions 19.

The blank, after being cut to the form shown in Figure 5, is then scored and folded at its vertical axis along the dotted line indicated at 20 in Figure 5 into the condition shown in Figure 6, namely with the score and fold extending centrally through the ears 18, while the prongs are bent substantially at right angles to the same side or face of the blank. The prongs 19 on opposite ends or sides of the blank are off-set or arranged in different transverse planes as shown in Figure 5.

The end of the head-strap 17 is then inserted between the side walls 21, 21 and these two side walls firmly pressed together thereby forcing the prongs 19 through the band 17, causing the clip 16 to be firmly gripped to the end of the strap therebetween.

The slot in the ear 14 is of length just sufficient to receive the main portion of the clip 16; while the width of the clip 16 at its outer or folded end, with the ears 18, is of dimensions greater than the length of the slot 15 in the ears 14 of the ventilating screen frame of the eye-cup. The slot 15 in the ear 14 of the eye-cup is of width suf-

ficient to permit the folded clip with the end of the head-band to pass therethrough. The clip, attached to the end of the head-band, is inserted edgewise through the slot, 5 namely by flexing the strap and passing the narrow side of the clip through the slot, as shown in dotted lines in Figure 7. It is apparent that as soon as the entire clip has been drawn endwise entirely through the slot 10 in the ear 14, the clip will immediately right itself into the full line position which will cause the ears 18 to engage with the forward outer side of the ear 14 and thus prevent detachment of the head-band or strap 17. 15 The construction shown and described, as is apparent, is inexpensive in manufacture, while at the same time ensuring positive attachment of the head-band, preventing the latter from becoming accidentally detached 20 or disconnected, but which will permit of detachment of the head-band when found necessary by simply drawing the end of the head-strap sufficiently through the slot 15 in the ear 14 to permit the clip portion 16 25 to be placed into the angular relation disclosed in dotted lines in Figure 7 which enables the clip to be endwise forced through the slot 15 of the ear 14.

In order to provide simple means whereby 30 the free ends of the head-straps 17 may be secured together into a head band of proper size to fit the head of the wearer, the straps 17 are shown provided with an elongated split ring 22, see Figure 1. This split ring is 35 of size just sufficient to permit the ends of both straps 17 to pass therethrough, so as to hold the two straps in close frictional relation with each other. The end of each strap is preferably looped or folded and stitched 40 into place so as to prevent the ring 22 slipping off the straps. By positioning the ring 22, adjacent to the looped outer end of one strap, the other strap may be adjusted so as to provide a band of proper size for the wearer after the goggle has been applied, namely by shortening the end of one strap from ring 22 to the attached or clip end thereof. The ring 22 causes the adjusted relation of the straps to be maintained; releasing of 45 the straps being induced by grasping ring 22 and pulling on the shortened end of the strap until the band can be slipped off the head.

The specific embodiment of the invention 50 has been described in terms employed merely as terms of description and not as terms of limitation, as structural modifications are possible without, however, departing from the spirit of my invention.

60 What I claim is:

1. In combination with the head straps of a goggle, holding means composed of a blank of sheet metal provided at its top and bottom marginal edges and intermediate of its ends 65 with extensions, the blank being folded back

upon itself with the ends of the straps therebetween.

2. In a goggle provided with head straps, a holding clip secured to each strap and composed of a flat sheet metal blank provided with opposingly arranged strap gripping surfaces, while the upper and lower marginal edges of the blank are provided with aligned extensions, the blank being folded about the strap end on a line disposed at the vertical axis of the blank through said aligned extensions. 70

3. In combination with the eye-cups of a goggle, each provided with a slotted ear, and head straps; of holding means secured to the ends of the straps and composed of a flat sheet metal blank, the upper and lower edges of the blank having aligned extensions, the blank being folded at its vertical axis through said extensions back upon itself with a strap-end therebetween, the blank at its opposite side edges being provided with prong extensions bent at an angle to the blank, in opposing off-set relation with each other and adapted to press into the straps, the folded end of the blank with said extensions being of width greater than the length of the slots in the ears. 80
